UNITED STATES PATENT OFFICE.

HARRY M. BRIDGES, OF OTTUMWA, IOWA, ASSIGNOR OF ONE-HALF TO
WILLIAM KLEE, OF SAME PLACE.

DESIGN FOR A CARPET-STRETCHER.

SPECIFICATION forming part of Design No. 25,256, dated March 17, 1896.

Application filed February 7, 1896. Serial No. 578,444. Term of patent 7 years.

To all whom it may concern:

Be it known that I, HARRY M. BRIDGES, a citizen of the United States, residing at Ottumwa, in the county of Wapello and State 5 of Iowa, have invented a new and original Design for Carpet-Stretchers, of which the following is a specification.

This invention relates to a new and original design for carpet-stretchers, and it has for its 10 object to provide a design of this character that shall be both useful and ornamental.

The leading features of the design reside in a truly rectangular body provided with an 15 arc-shaped top edge, an aligned series of conical figures projected from said top edge, and opposite parallel side portions having at their lower extremities semicrescent-shaped figures projected below and at one side of the bottom edge of said body at an obtuse angle 20 thereto.

In the drawings, Figure 1 is a perspective view of a carpet-stretcher embodying the herein-described design. Fig. 2 is a side edge view thereof.

Referring to the accompanying drawings, 25 the numeral 1 designates a truly rectangular body, the top and bottom and opposite side edges of which are parallel. The body 1 is provided with an arc-shaped top edge, 2, from which top edge is projected an aligned series 30 of conical figures 3, and at opposite side edges the said body is provided with the parallel side portions 4, having at their lower extremities semicrescent-shaped figures 5, projected below and at one side of the bottom edge, 6, of 35 said body at an obtuse angle thereto.

What I claim is—

The design for a carpet-stretcher herein shown and described.

In testimony that I claim the foregoing as 40 my own I have hereto affixed my signature in the presence of two witnesses.

HARRY M. BRIDGES.
